ATTORNEY

UNITED STATES PATENT OFFICE

WALTER O. WILLE, OF WATERLOO, IOWA, ASSIGNOR TO CLAY EQUIPMENT CORPORATION, OF CEDAR FALLS, IOWA

LEVER STALL

Application filed October 27, 1930. Serial No. 491,390.

My invention relates to improvements in lever stalls, and the object of my improvement is to supply in such a stall, a pair or pairs of stanchions so suspensively supported and mounted as to have limited rocking movements on a common axis while allowing swinging displacements of one stanchion relative to the other and non-swinging stanchion.

Another object of my improvements is to combine with the swinging stanchion of each pair, means for releasably swinging it to and from the other stanchion, with other means for releasably locking the swinging stanchion in one position when said operating means are disengaged therefrom.

Another object of my improvements is to arrange said stanchion operating means as to be placed beyond a dead center in one of its elements to releasably lock said means in holding a swinging stanchion closed against a non-swinging stanchion associated therewith.

These objects I have accomplished by the means which are hereinafter described and claimed, and which are illustrated in the accompanying drawing, in which Fig. 1 is a front elevation of a lever stall device equipped with a pair of hinged stanchions mounted and supported operatively therein according to my invention, and with parts in section or broken away. Fig. 2 is a top plan of the parts shown in said Fig. 1. Fig. 3 is an enlarged detail perspective view of an apertured slide or bearing member of the device as associated with the upper termination of a swinging stanchion. Fig. 4 is an enlarged detail view, in top plan and with parts of the track rails in longitudinal section, wherein the fixed arcuate supporting member for the non-swinging stanchion of a pair is supported for rocking slidably laterally thereon. Fig. 5 is an enlarged side elevation of an engaging catch used to operatively and releasably interlock with said slide bearing member.

In said Fig. 1 are shown fixed longitudinally spaced tubular posts 1, connected at their tops on either side by channel bar rails 2 and 3 with facing flanges spaced apart providing an elevated fixed track, for a lever

55 Positioned midway between said posts 1 is a pair of vertically disposed basally hinged stanchions 5 and 6 suspended normally in a vertical plane medial with the interspace of the track rails 2 and 3, the stanchions being spaced apart as usual with converging and approximated lower and upper terminations, the former overlapping hinged on a cross 60 pintle 7 and the latter secured by bolts 12 to upright facing hollow semicircular terminals 13 and 15 whose stems when closed together provide a substantially circular supporting means for the stanchion parts 5 and 6.

To prevent excessive displacements of the lower part of the stanchions, any convenient 65 or usual means of limitation therefor may be provided, such as chain links 9 connected between the base of the stanchions medially and a supporting floor below by connections 10.

70 Referring to said Fig. 4, the numeral 18 denotes a pair of plate members fitting the inner web walls of the spaced rails 2 and 3 and secured thereto as by headed screws 51. At one end of each these members are connected transversely across the interspace of the rails 75 by an arcuate horizontal bearing part 17, substantially semicircular and of rounded cross section. The terminal 13 of the stanchion 5 has its end part 14 shaped as a hook of considerable width and fitted to the arcuate element 17 to be suspended thereon removably and in sliding rocking engagement therewith suspensively, whereby the stanchion may rock laterally horizontally together with the other stanchion 6 on a common axis of rotation.

80 The numeral 19 denotes a slide bearing plate having at opposite ends downwardly inclined terminations 24 and 25, the latter depending into the interspace of the upper 85 flanges of the rails 2 and 3 while the wider body of the plate rides slidably upon the tops of the rails. As shown in Fig. 3, a guide bar 26 is secured by screws 27 across the under side of the plate 19, the bar having offset ends 90 to ride under the upper flanges of the rail members 2 and 3, to prevent displacement upwardly of the plate.

95 The slide plate 19 has near opposite ends the like rectangular slots 22 and 23, and also 100

has a medial aperture 20 with raised rim partially therearound, being circular with a segment removed transversely relative to the plate, but having at the middle of the chord 5 and of less width an inwardly directed and upwardly inclined pyramidal boss 21 extending toward the center of the aperture. The upper termination of the stanchion part 15 has an outer boss or lip 16, serving as a stop 20 against the plate to prevent the part 15 escaping downwardly through the aperture 20 when the stanchions are suspended, but the lipped end may be inserted initially by tipping this stanchion relatively to the plate. 15 The inner boss 21 of the plate is shaped and positioned so as to keep the semicircular stanchion part 15 seated in the aperture coaxially, yet allows the rocking of the part 15 through a considerable arc of movement 20 around the point of the boss to correspond with the like arc of movement permitted the other stanchion 5 in moving around the semicircular connection 17 also co-axially, when the stanchions are closed.

25 To lock the slide plate 19 to the track when the pair of stanchions 5 and 6 are closed together, the plate 19 being in the position shown in Fig. 2, a catch 48 pivoted on a cross-bolt 47 between the rails 2 and 3 may be 30 swung over to engage its angular tip 49 in the aperture 23 of the plate.

Means for swinging the stanchion 6 from and toward the stanchion 5 are provided. A manually operable angular arm 33 is pivoted 35 at its angle on a pintle 32 fixed to the track near one end. The free end part of the arm when the stanchions are closed depends downwardly alongside an end post 1, and its termination is received in an offset part or socket member and stop 35 on a plate 34 fastened on the post, the arm being then in or beyond a dead center position relative to a link-bar 30 pivoted terminally to the other end of the arm on a pintle 31. This link-bar 30 substantially parallels the adjacent rail 2 and has a pivotal connection at 29 with a medial part of another parallel rod 28 just above the top of the track on one side.

Referring to Fig. 5, the numeral 42 denotes 40 a catch having tubular ends 45 secured rockingly non-slidably on said rod 28 in a location which, as shown in Fig. 2, permits it to be swung over to engage its angular tip 43 in the aperture 22 of the slide plate 19 when the latter is positioned together with the stanchion 6 in a closed position of the latter. When so engaged, the other catch 48 may be 45 swung to disengage it from the plate 19, and then the arm 33 may be swung in a direction oppositely to thrust the rod 28 with the now connected slide plate 19, to swing the stanchion 6 to an opened position indicated by the dotted lines in Fig. 1. In this position of the arm 33 it passes to or beyond a dead

center to releasably lock it there with the stanchion 6 opened.

It will be understood that the mounting of the two terminals 13 and 15 on the semicircular connection device 17 and in the aperture 70 20 of the slide plate 19 on a common axis for rotation or rocking movements, permits to such stanchions when closed particularly sufficient lateral play at all times to comfortably accommodate the stanchions to an animal's neck during any considerable number and scope of movements thereof.

It should be further noted, that when as usual, a plurality of pairs of such stanchions are aligned along the track rails, an operator may swing open any desired number of the stanchions 6 to thus release the animals, without releasing any animal or animals still confined in an unoperated pair or pairs of such stanchions, for the latter may be initially locked in closed position by the catches 48, and the other catches 42 disengaged from the slide plate 19. The catch 42 may have a medial longitudinal rib with a fingerhold aperture 44 for convenient use in operating it.

An arm 37 may be end-pivoted to the rod 28 and have its other end pivoted at 38 to an arm 39 and to a standard stop member 41, which latter as shown in dotted lines may be extended by action of the rod 28 when moved in one direction, to block the opening between a post 1' and the next adjacent stanchions, to prevent an animal from pushing its head through their interspace.

Having described my invention, what I claim as new, and desire to secure by Letters Patent, is:

1. In a lever stall, an elevated track, a pair of movably connected stanchions positioned thereunder with approximated upper ends, a bearing element movable along said track and apertured to receive one of said stanchion ends both slidably and rockingly, and an arcuate cross member fixedly secured across said track with its axis that of the aperture in the bearing member in one position of the latter, the other of said stanchions having its upper end part hook shaped to engage and ride upon said arcuate cross member when the stanchions are closed together and rocked as one together laterally.

2. In a lever stall, an elevated track, a pair of movably connected stanchions positioned thereunder with approximated upper ends of different lengths, a bearing element movable along said track and apertured with a reentrant boss to receive the longer end part of one stanchion slidably and rockingly with a restricted scope of rotation, 125 an arcuate cross member secured on said track, the shorter end part of the other stanchion being hooked to movably engage and ride upon said cross member when the stanchions are rocked laterally, and means releasably con-

- nected to said bearing element to shift it along said track.
3. In a lever stall, an elevated track consisting of laterally spaced rails, a pair of 5 hingedly connected stanchions positioned under the interspace of the rails and having approximated upper ends of which one is longer than the other, a bearing element movable along said track and apertured to receive 10 the longer end part of one stanchion both slidably and rockingly, an arcuate cross member crossing the interspace of said rails and end connected thereto, the shorter upper end of the other stanchion being hooked to ride upon 15 said arcuate member slidingly when the stanchions are rocked laterally, means releasably connected to said bearing element to shift it along said track, an operating lever movably connected to said means to pass its dead 20 center in either of opposite directions to lock the bearing element with the stanchions open or closed, and a catch movably mounted on said track and releasably engageable with said bearing element when said operating 25 means is disengaged therefrom, to hold the bearing element with the stanchions closed together.
4. In a lever stall, an elevated track consisting of laterally spaced rails, a pair of 30 hingedly connected stanchions positioned under the interspace of the rails and having approximated ends of which one is longer than the other, an apertured bearing element movable along said track and one aperture 35 of which is substantially circular with an inwardly directed boss, the approximated upper ends of the stanchions both being of semi-circular cross section with the longer upper end part of one stanchion mounted both slid- 40 ingly and rockingly in said circular aperture of the bearing element, the boss whereof serves to limit the rocking of the traversing stanchion end to a limited predetermined degree, an arcuate cross member between 45 said rails and end connected thereto, the shorter upper end of the other stanchion being hooked over said arcuate member to be supported and ride thereupon laterally when the stanchions are rocked laterally, releas- 50 able operating means connected to said bearing element to shift it along said rails, and including an operating lever, and a catch mounted hingedly upon one of said rails to releasably engage another aperture in said 55 bearing element to hold the plate and stanchions locked to the track in a closed position of the stanchions, and after release of said operating means from the bearing element.
- 60 5. In a device of the character described, an elevated and end supported horizontal arcuate member, a bearing element supported adjacent thereto and having an aperture coaxial with the axis of said arcuate mem- 65 ber and movable to and from it, and a pair of stanchions hingedly connected at their lower ends and having the upper terminal of one stanchion slidably supported on said arcuate member, and the upper termination of the other stanchion mounted both slidably 70 and rockingly in the aperture of said bearing element.
6. In a device of the character described, an elevated and end supported horizontal 75 arcuate member, a bearing element supported adjacent thereto and having an aperture coaxial with the axis of said arcuate member and movable to and from it, and a pair of stanchions movably connected at their lower ends and having the upper terminal of one 80 stanchion movably supported on said arcuate member, and the upper termination of the other stanchion extended loosely slidably and rockingly through the aperture of said bearing element and having a terminal boss 85 thereon as a stop to prevent egress thereof of the depending stanchion.
- In testimony whereof I affix my signature.
